DISPENSING CONTAINER

John B. Ames, Box 670, Marion, Ala. 36256

Filed Sept. 15, 1971, Ser. No. 180,946

Term of patent 14 years

Int. Cl. D9—01

U.S. Cl. D9—71

FIG. 3

FIG. 1

FIG. 2

FIG. 4

FIG. 1 is a side elevational view of a dispensing container showing my new design;
FIG. 2 is an end elevational view;
FIG. 3 is a top plan view; and
FIG. 4 is a bottom plan view thereof.

I claim:

The ornamental design for a dispensing container, substantially as shown.
